DESIGN FOR A COMBINATION RADIO AND LAMP

James Robinson, Jr., Cleveland, Ohio

Application January 2, 1947, Serial No. 135,902

Term of patent 14 years

(CL. D56—4)

To all whom it may concern:

Be it known that I, James Robinson, Jr., a citizen of the United States, residing at Cleveland, in the county of Cuyahoga and State of Ohio, have invented a new, original, and ornamental Design for a Combination Radio and Lamp, of which the following is a specification, reference being had to the accompanying drawing, forming a part thereof, wherein:

Figure 1 is a front view of a combination radio and lamp embodying my new design.

Figure 2 is a side view of the same.

Figure 3 is a rear view of the same.

I claim:

The ornamental design for a combination radio and lamp, substantially as shown.

JAMES ROBINSON, JR.
